UNITED STATES PATENT OFFICE.

PHILIP H. BEVIER, OF BROOKLYN, NEW YORK.

REINFORCED FLOOR CONSTRUCTION.

Application filed November 13, 1920. Serial No. 423,873.

To all whom it may concern:

Be it known that I, PHILIP H. BEVIER, a citizen of the United States, residing at the city of New York, borough of Brooklyn, county of Kings, and State of New York, have invented a certain new and useful Reinforced Floor Construction, of which the following is a specification.

This invention is a reenforced floor construction wherein hollow tiles are bonded to and interlocked with concrete material in a manner to utilize the compressive strength of the tile material and the concrete material, said concrete material being in the form of intersecting ribs which are reenforced by the presence of metal rods embedded in said material at the lower chord of the composite slab.

In constructing the floor slab it is usual to position the tiles in rows, each tile being spaced relatively to other tiles, the rods are placed in the spaces between the tiles, the rods extending in one direction crossing the rods extending in an opposite direction, and to deposit plastic or semi-plastic concrete material in the spaces between said tiles, the concrete material being tamped in place for filling the spaces at the sides and open ends of the tiles, said concrete material when set producing intersecting beams or ribs which are bonded to the tiles.

The plastic or semi-plastic concrete material is free to enter the open ends of the hollow tiles, in order to effect an interlocking engagement between the ribs and the resulting concrete ribs or beams; but the extent to which said plastic concrete enters the cells or spaces of the tiles depends in a large measure upon the consistency of said material, for obviously wet concrete is free to flow into and through the unobstructed open spaces or cells of the tiles.

The object of my invention is to control the entry of the concrete material into the spaces or cells of the tiles to a definite extent, such control being attained irrespective of the consistency of the material, whereby the concrete is precluded from passing beyond predetermined limits into the cells of the tiles and a definite quantity of the material is obtained within definite limits at the previously open ends of said tiles in order to obtain, transversely to the length of each tile, a section composed partly of tile material and partly of concrete material.

In my floor slab, the end portions of

each tile are embedded in the concrete material composing the ribs or beams, the concrete material entering the cells of the tiles operating to stiffen the material of said tiles against transverse pressure.

The invention, briefly stated, is a concrete stopper positioned in such relation to the tile as to arrest within definite limits the entry of the concrete material into and within the spaces or cells of said tile. Said stopper is of such form that it produces pockets for the free entry of the concrete material into the cells of the tile, which pockets allow said concrete to have access to the tile material so as to become bonded therewith at the sides of the tile and also interiorly thereof.

Other features and advantages of the invention will appear from the following description taken in connection with the drawings, wherein—

Figure 1 is a plan view of a certain area of the floor construction, the concrete ribs being partly broken away to show the tiles and the rods in full lines.

Figure 2 is a vertical cross section through the slab, said view being taken in the direction of the cells through the tiles.

Figure 3 is a vertical section taken transversely through an end portion of the tile and a portion of the concrete rib, the plane of the section being indicated by the dotted line 33 of Figure 2.

Figure 4 is an end view of one form of the tile showing the concrete stoppers in position relatively to the cells of said tile.

Figures 5 and 6 are perspective views of other forms of cellular tiles each provided with my devices for limiting the entry of the concrete material into the open ends of the cells.

Figure 7 is a vertical section through the adjacent portions of two cellular tiles of the form shown in Figure 6, illustrating the manner of arresting the entry of the concrete material into the cells of said tiles.

Figure 8 is a vertical transversal section through one tile, the concrete stoppers therein, and sections of the concrete material, the plane of the section being indicated by the dotted line 8—8 of Figure 7.

Figures 9 and 10 are perspective views of the concrete stoppers adapted for use in connection with the 6 cell tile of Figure 5 and the 9 cell tile of Figure 6, respectively.

Figures 11 and 12 are detail plan views of

the blank, either of which may be used for producing the stopper of Figure 9, and

Figure 13 is a detail plan view of the blank used in producing the stopper of Figure 10.

As shown in the drawings, the floor slab consists of tiles A, rods B B', and concrete ribs or beams C C', the general form of which is known in the art as a two way reinforced floor construction. Tiles A are laid in rows extending in two directions, said tiles being in spaced relation to form spaces α between the sides of the tiles and other spaces α' between the ends of the tiles in adjacent rows, see Figure 1. Rods B are positioned in the spaces α and rods B' in the spaces α' , the two series of rods crossing each other at a right angle and said rods being in the lower chord of the slab, see Figures 2 and 7.

After the tiles and the rods shall have been assembled, concrete material is deposited in the spaces α and α' and tamped to completely fill said spaces, said concrete material constituting the ribs or beams C C'; the beams C extending in one direction and the beams C' in an opposite direction, whereby the beams or ribs are in intersecting relation to each other.

The concrete ribs encase the rods and are bonded to the tiles, and in the operation of filling the spaces α with plastic, or semi-plastic, concrete material, and of tamping the same, some of said concrete material enters the cells of the tiles at the open ends thereof. The extent to which the concrete material enters the tiles depends, more or less, upon the consistency of the mixture, and in case wet concrete happens to be used, then it is apparent that the more or less fluid portion of the mixture will flow clear through the cells of the tiles, involving waste and loss of the material.

According to my invention, provision is made for arresting in a positive manner the entry of the concrete material into the tiles, and for limiting to a prescribed extent, the quantity of concrete material which is allowed to fill the end portions of the cells of the tiles. To these ends, I employ a device, herein referred to as a stopper, which is positioned, at least partially, within the tile, said stopper being so fashioned or constructed as to produce pockets for the reception of some of the concrete material and said stopper operating to close or block off the cells of the tile in order to exclude the concrete material from the tile cells except at the pockets.

Various forms of constructions may be employed as the stopper, but in Figures 1, 2, 3, 4, 5 and 9 there is shown a practical stopper E for a 6 cell tile, whereas in Figures 6, 7, 8 and 10 a stopper F for a 9 cell tile is illustrated.

The stopper E is shown in Figures 11 and 12 as comprising a flat rectangular blank D of appropriate material, such as sheet metal, paper, or any other material suitable for the purpose, said stopper-blank D being provided intermediate its ends with a slot d. When composed of paper, as in Figure 11, the blank is scored or creased as at d', but in case a sheet metal blank is used as in Figure 12, it is provided with the slot d and with lines of weakness at d', the scoring or line of weakness in either form of blank being provided to facilitate the operation of bending the blank as well as to determine the lines on which the blank is required to be bent in order that the resulting stopper may be fitted accurately to the tile.

The 6 cell tile of Figures 2, 3, 4 and 5 is provided with vertical webs e and horizontal webs e' positioned interiorly of the walls to sub-divide the chamber into six cells, and such a tile requires three of the stoppers E, shown in Figure 9, the same being formed from either the paper blank of Figure 11 or the metal blank shown in Figure 12. Said stopper E is formed by bending the material of blank D on the lines of weakness to produce the loop f and the diverging members f', the slot d being in the closed end of the loop f. Said stoppers, and each of them, are positioned for the loops f to embrace the edges of webs e, whereas the diverging members f' extend across the cells, as clearly shown in Figures 2 and 6. The frictional contact of the stopper with the tile retains the stopper in operative position, the closed end of the loop f in contact with web e' arresting the inward movement of said stopper with respect to the cells of the tile. The diverging members f' of the stopper extend across the cells at an angle to the length thereof, said members f' producing pockets g at the ends of the cells (see Figure 5), which pockets are open for the free entry of the concrete material, whereby the concrete from the ribs or beams C' is adapted to fill the pockets g and to unite with or become bonded to the clay material of the tile on the interior thereof so as to produce transverse sections of solid material composed partly of the tile material and partly of concrete material, see Figures 2 and 3. This partial entry of the concrete material into the cells of the tile results in the formation of keys c which are bonded to the webs and walls of the tile on the interior thereof and within predetermined or definite limits as depicted in Figures 2 and 3, the entry of the concrete keys c into the tile cells serving the important function of increasing the stability of the tile transversely thereof at the end portion which is embedded in and interlocked with the concrete material of the ribs or beams C'.

The stopper thus performs the important

function of arresting the flow of the plastic material into or within the cells of the tile to an undesirable extent, while at the same time the formation of the stopper to produce 5 the pockets enables a relatively small quantity of the concrete material to enter the tile cells and to become united with or bonded to the tile material.

The function of the slot *d* in the stopper 10 of Figures 5 and 9 is to expose the tile material at the edge of the web *e'* of the tile when the stopper is fitted to said web, whereby the concrete material of the beam or rib *C'* may unite with and become bonded to the 15 webs as well as with the walls of the tile.

It will be noted that the loop of the stopper device is positioned into contact with one of the cross webs of the tile block, whereby 20 said loop arrests the movement of the stopper in one direction when assembling the stopper relatively to the tile block. The act of placing the stopper into place relatively to the tile block also serves to position the inclined members within the open ends of the 25 cells of said tile block, and in so placing the stopper in position the free ends of the inclined members are brought into frictional contact with the inner surfaces of the walls of the tile block, see Figure 2. The inclined 30 members are at an angle to the medial line of the loop and said members are free at the other ends thereof, whereby the assemblage of the stopper relatively to the tile block not only positions the loop into engagement with 35 the cross web of said tile block but the inclined members of said stopper are introduced within the open ends of the cells in such manner that the free ends of said inclined members will have a desired frictional 40 contact with the inner surfaces of the walls of the tile block. This attains a useful purpose, for the reason that the loop in engagement with the web of the tile block arrests the motion of the stopper in one direction, so as to limit the entry of the stopper 45 into the block, whereas the frictional contact of the inclined members of the stopper with the walls of the tile block act to arrest the movement of the stopper, when it shall 50 have been applied, in an opposite direction, and thus the stopper is so frictionally held on the tile block that it is not pushed inwardly by the pressure of the concrete material, nor can the stopper be detached accidentally 55 when it is fitted to the open end of said tile block prior to laying said block upon the centering, as usual in the art. Those skilled in the art are aware that a narrow fin or ledge is almost invariably produced at or around the open ends of the cells in tile blocks and when my stopper is applied, the free ends of the inclined members snap into place in the rear of the fin or ledge present on said block, so that the inclined 60 members of the stopper will be so locked in 65

position as to preclude the withdrawal of the stopper from the open end portion of the cellular block.

The stopper *F* for use in connection with a 9 cell tile is modified to suit the height of 70 said tile and the tier of cells therein, said stopper comprising loops *h h'*, diverging members *i i'* and an inclined member *j* connecting the loops *h h'*, the stopper being bent from a blank *F'* of Figure 13. Said blank 75 *F'* is somewhat longer than the blank *D* of Figures 11 and 12, being scored or weakened on lines *k* and provided with a plurality of slots *k'*. The blank is bent on the score lines to produce the loops and the inclined members, and the stopper is adapted to be used on the cross webs *e'* of the tile by slipping the loops *h h'* into frictional contact with the webs, whereby the inclined members 80 *i i' j* extend across the cells as in Figure 7 for 85 arresting the entry of the concrete material into the cells except to the extent permitted by the pockets which are formed by the stopper, which pockets admit concrete to a limited extent into the cells of the tiles so as 90 to produce the keys *e* which material while in a plastic condition is free to adhere to and become bonded to the webs and walls of the tile interiorly thereof so as to produce solid sections transversely of the tile (see Figure 95 8) composed partly of tile material and partly of concrete material. The slots *k'* in the loops of the stopper *F* expose the edges of the webs *e'* in the tiles to the accession of the concrete material constituting the ribs 100 or beams *C'*, and thus the concrete while plastic is free to bond with the tile both on the inner and outer surfaces of said tile and at the edges of the webs of said tile.

It is apparent that the stopper may be 105 bent easily and quickly from the preferred blanks, and that each stopper can be placed in position by unskilled labor, thus making provision for arresting the entry of the concrete into the tiles by a simple and economical expedient.

As in the construction heretofore described, the stopper includes inclined members extending at an angle to the medial lines of the loops, said inclined members being adapted for frictional engagement with the interior surfaces of the walls of the tile block or to be positioned inwardly of the fin or ledge at the open ends of the cells in said block, whereby the free ends of the inclined members have such contact with the tile block as to arrest the movement of the stopper in an outward direction relatively to the block, the loops in contact with the cross webs arresting the movement of the stopper 120 inwardly of the block.

Having thus fully described the invention, what I claim as new and desire to secure by Letters Patent is:

1. In a floor slab, the combination with 130

- cellular tile, and concrete material, of a stopper provided with a loop positioned in contact with a web of said tile, said stopper being provided with members inclined to the 5 medial line of said loop and said inclined members having their free ends in frictional contact with the interior surfaces of the walls of said cellular tile, whereby said stopper is retained in position against displacement either outwardly or inwardly 10 with respect to said tile.
2. In a floor slab, the combination with a cellular tile, and concrete material, of a stopper having a loop in contact with a web 15 of said tile for arresting the movement of said stopper inwardly of the tile cells, said stopper being provided with a plurality of members each inclined at an angle to the medial line of the loop and each positioned 20 within a tile cell for the free end of said inclined member to have frictional contact with the interior surface of a wall of said tile, said inclined members extending transversely within the cell at an angle thereto 25 and producing within an open end of said cell a pocket adapted to receive said concrete material.
3. In a floor slab, the combination with a cellular tile, and concrete material, of a stopper provided with a loop embracing a web of said tile, said loop having intermediate the edges of the stopper a transverse 30 opening through which is exposed a marginal part of the web for the accession of the concrete material, said stopper being provided with a plurality of members inclined to the medial line of the loop and said members being positioned interiorly of the cells and with the free ends of said inclined members in contact with the interior 35 surfaces of the tile, whereby said inclined members contacting with the tile retains the stopper against displacement outwardly with relation to the tile.
4. In a floor slab, the combination with a cellular tile, of a stopper provided with a plurality of members unitary therewith, and positioned interiorly of the cells of said tile, said members being inclined transversely to the longitudinal axis of the cells 45 and the free ends of said inclined members being in frictional contact with the tile interiorly thereof whereby said stopper is retained against displacement outwardly with respect to said tile.
5. In a floor slab, the combination with a cellular tile, of a stopper provided with a plurality of members unitary therewith and positioned within the cells of said tile 50 for the free ends of said members to have frictional contact with the tile, each of said members being inclined from the line of contact of said free end inwardly with respect to the open end of the tile whereby the stopper as a unit is retained in position 55 against displacement outwardly with respect to the tile and said members produce pockets at the open end of the tile for the entry of concrete material.
6. In a floor slab, the combination with a cellular tile, and concrete material, of a stopper embodying a loop and a plurality of members inclined outwardly from said loop, the loop of the stopper having frictional contact with a web of the tile and 75 said inclined members of the stopper having frictional contact at the free ends thereof with the tile interiorly thereof whereby said stopper is retained against displacement outwardly with respect to said tile. 80
7. In a floor slab, a cellular tile, a stopper compressible for insertion substantially within cells of said tile, said stopper including a loop and said loop being provided intermediate the edges of the stopper 85 with a slot, said loop being engageable with a partition of the tile to expose the slot intermediate the top and bottom of said tile, and concrete material entering the cells of the tile to the extent permitted by the stopper, said concrete material filling the slot of the stopper loop and being bonded with the partition of said tile. 90
8. In a device of the class described, a compressible tile stopper embodying a loop 95 and a plurality of freely yieldable members extending in opposite directions from said loop, whereby said stopper is compressible for insertion within the cells of tile and the free ends of said members are adapted for 100 frictional contact with the tile walls interiorly thereof.
9. In a device of the class described, a compressible tile stopper embodying a loop and a plurality of freely yieldable members inclined relatively to the medial line of the loop, said loop being provided with a slot the boundary edges of which are within the margins of the stopper. 105
10. In a device of the class described, a compressible tile stopper embodying a loop and a plurality of members extending in opposite directions from said loop and inclined to the medial line thereof, said members being yieldable relatively to the loop 110 and the outer ends of said members being free. 115

In testimony whereof I have hereto signed my name this 11th day of November, 1920.
PHILIP H. BEVIER.
